UNITED STATES PATENT OFFICE.

JEANE D. GUNDER, OF CHICAGO, ILLINOIS.

DESIGN FOR A BOX.

47,692.

Specification for Design. Patented Aug. 10, 1915.

Application filed May 28, 1915. Serial No. 31,069. Term of patent 14 years.

To all whom it may concern:

Be it known that I, JEANE D. GUNDER, a citizen of the United States, residing at Chicago, in the county of Cook and State of Illinois, have invented a new, original, and ornamental Design for Boxes, as shown in the accompanying drawing and described in the following specification.

Figure 1 is a plan view of the box. Fig. 2 is a view of the box in side elevation. Fig. 3 is a view of the box in end elevation illustrating my new design.

The design comprises the general shape and proportions of the box together with the fluting, scrolls and shield appearing upon the top of the box, and the beading appearing about the sides and ends of the box.

I claim:

The ornamental design for a box as shown and described.

JEANE D. GUNDER.
